UNITED STATES PATENT OFFICE.

JOHN S. LARSEN AND ANTON VALERIUS, OF NEW YORK, N. Y.

DESIGN FOR A METAL PLATE.

42,765.

Specification for Design.

Patented July 9, 1912.

Application filed April 6, 1912. Serial No. 689,087. Term of patent 7 years.

To all whom it may concern:

Be it known that we, JOHN S. LARSEN and ANTON VALERIUS, subjects of the King of Denmark and residents of the city of New York, borough of Manhattan, in the county and State of New York, have invented a new, original, and ornamental Design for a Metal Plate.

Reference is to be had to the accompanying drawing, in which the figure is plan

view of the design for a metal plate or similar article.

We claim:

The ornamental design for a metal plate, as shown.

JOHN S. LARSEN.
ANTON VALERIUS.

Witnesses:

CHAS. WHITEHEAD,
MERCY VINCENTI.
